UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

TRIMMING MECHANISM FOR SEWING MACHINES.

Application filed October 18, 1921. Serial No. 507,443.

The invention relates to new and useful improvements in trimming mechanism for sewing machines, and more particularly a trimming mechanism having a movable trimming blade mounted on the overhanging arm and a stationary ledger blade mounted on the work support.

An object of the invention is to provide a trimming mechanism of the above character with interchangeable ledger blades and means whereby the position of the movable blade on the supporting means may be shifted transversely of the path of reciprocation of the needle to position the movable trimming blade for proper co-operative action with the selected ledger blade.

A further object of the invention is to provide a trimming mechanism wherein the movable trimming blade is carried by a pivoted support and is yieldingly pressed into engagement with an adjustable stop, so that the pressure of the blade against the ledger blade may be varied.

A further object of the invention is to provide a support for the movable trimming blade of the above character, wherein the pivotal support is so disposed relative to the means for shifting the blade laterally that the angle of reciprocation of the blade may be varied within certain limits.

These and other objects will in part be obvious and will in part be hereinafter more fully disclosed.

In the drawings which show by way of illustration one embodiment of the invention—

Figure 1 is a view partly in front elevation and partly in vertical section, showing a sewing machine embodying my improvements;

Figure 2 is a view partly in front end elevation and partly in vertical section of the same;

Figure 3 is a view partly in plan and partly in section of the forward end of the work support and the parts immediately above the same;

Figure 4 is a perspective view of the supporting means for the movable trimmer;

Figure 5 is an enlarged vertical sectional view on the line 5—5 of Figure 4;

Figure 6 is a sectional view on the line 6—6 of Fig. 5.

The invention is directed to a trimming mechanism of the type shown in the patent

granted to Muther, Holland & Woodward November 2, 1897, No. 592,806. The trimming mechanism of said patent consists of a stationary ledger blade mounted on the work support and a movable trimming blade mounted on the overhanging arm. This movable trimming blade is reciprocated in a vertical plane. The needle bar is carried by a support capable of being shifted transversely so that the position of the line of stitching may be shifted toward or from the trimming blade within a limited range of adjustment. When it is desired, however, to get wider ranges of adjustment, so that the trimming of the edge will be farther from the line of stitching than can be accomplished by adjusting the position of the needle bar, then interchangeable supports for the movable trimming blade are provided so that the movable blade may be set at different distances from the center of the needle hole in the throat plate and interchangeable throat plates are provided with ledger blades properly positioned to co-operate with the trimmer blade in its shifted positions.

The present invention is directed to the support for the movable trimming blade which permits the movable trimming blade to be shifted without removing and replacing the support for the trimming blade as heretofore.

In the broad aspect of the invention, the movable trimming blade is carried by a shiftable head. This shiftable head is positively moved so as to shift the position of the movable trimming blade transversely of the line of reciprocation of the needle. Locking means is provided for holding the shiftable head in its various adjusted positions. Thus it is that the trimming blade may be readily set to co-operate with the properly selected ledger blade so as to trim the desired distance from the line of stitching. The trimming blade is mounted directly on a pivoted support carried by the shiftable head and this pivotal support is yieldingly swung so as to press the movable trimming blade with a yielding force against the ledger blade. A stop screw is provided to limit this movement of the movable blade toward the ledger blade. Means is also provided for varying the tension of the spring and an adjustable screw is so set that the pressure of the upper knife or

movable blade against the lower knife or ledger blade may be increased or decreased. Through the combined adjustments of the shiftable head and the pivotal support the angle of the movable blade to the vertical may be adjusted.

Referring more in detail to the drawings, I have shown the invention as applied to a sewing machine which includes a work support 1, an overhanging arm 2, carrying a needle bar gate 3, in which a needle bar 4 reciprocates. Said needle bar carries a needle 5. The needle bar gate is pivoted at 6 to the overhanging arm. Projecting laterally from the needle bar gate is an arm 7 which is provided with a suitable recess adapted to engage a cam or eccentric on the shaft 8, and this shaft 8 is adapted to be shifted by means of an arm 9 and the amount 10 of movement which may be imparted to the shaft 8 is limited by a pin 10 adapted to engage stop screws 11 and 12, disposed on opposite sides of the pin.

Co-operating with the needle beneath the work support is a looper 13. Said looper is carried by a looper support 14, pivoted at 15 to a looper rocker 16. The material is fed across the work support by means of a feed dog 17, carried by a feed bar 18, which is 20 attached to a feed rocker 19. This feed dog 17 is located beneath the work support. The parts above described are all shown and described in detail in the patent to Muther et al. No. 592,806, above referred to, and further description of these parts is not thought necessary.

Co-operating with the feed dog 17 above the material is a feed dog 20. This feed dog 20 is carried by a feed bar 21 which is moved 40 back and forth by the rocker 19 and said feed bar is raised and lowered by means of an eccentric 22 on the main shaft 23. The material is held on the work support by means of a presser foot 24, carried by a presser bar 25.

The work support 1 is provided with a throat plate 26. Said throat plate 26 carries a bar 27, formed with a needle hole 29 and a recess portion forming a ledger blade 30 on said bar 27. Co-operating with this stationary ledger blade on the throat plate is a movable trimming blade 31. The work support 1 is provided with a recess 32 in which is located a spring-pressed member 33 which bears lightly against the trimming blade and 50 closes the opening in the work support around the trimming blade. The movable trimming blade 31 is rigidly clamped to a pivotal support 34. Said support 34 is pivotally carried by a shiftable head 35. A pivot pin 36 passes through the support into the shiftable head 35, see Fig. 6. Said pivotal support is provided with a projecting sleeve 37 which is formed integral with the pivotal support and increases the bearing support therefor. The pin 36 passes through

this projecting sleeve. The movable blade 31 is secured to the pivotal support 34 by means of a screw 38 which passes through an elongated slot 39 in the blade. This elongated slot permits the blade to be raised and lowered so as to be brought into proper co-operative action with the ledger blade on the throat plate of the machine. The shiftable head 35 is provided with a recess which engages a fin 40 on the bracket 41. This fin and recess are so located that the shiftable head may be moved longitudinally thereof and transversely of the line of reciprocation of the needle. The bracket 41 is provided with a recess 42 in which is located an adjusting screw 43. Said adjusting screw 43 is threaded into the bracket. Said adjusting screw is provided with a collar 44, spaced slightly from the head of the screw and the shiftable head 35 is formed with suitable recesses to receive the head of the screw and the collar 44, so that when the screw is turned the shiftable head will be positively moved on the bracket 41 toward and from the line of reciprocation of the needle. Said shiftable head is provided with a slot 45 through which a screw 46 passes and this screw is threaded into the bracket 41 and serves to lock the shiftable head in adjusted positions and prevents the same from creeping one way or another by accidental turning of the screw 43.

The pivotal support for the trimming blade is swung so as to press the movable blade against the ledger blade by means of a spring 47. Said spring 47 bears at its lower end on an arm 48 projecting outwardly from the support 34. This spring is located in a sleeve 49 which is capable of being adjusted in an arm 50, carried by the shiftable head. Through the adjustment of this sleeve the pressure of the spring on the arm 48 may be adjusted. A limiting screw 51 is carried by an arm 52 projecting outwardly from the shiftable head 35, and serves to limit the downward movement of the arm 48. This screw however is so positioned as to allow the movable trimming blade to bear with yielding pressure against the ledger blade and this pressure may be increased or decreased by varying the tension of the spring 47.

The bracket 41 forms a part of the yoke 53. The upper member 54 of this yoke, together with the bracket member 41, slide vertically on the presser bar and the yoke is reciprocated by means of a link 55 which is connected to an arm 56 carried by the shaft 57. The shaft 57 is oscillated by means of an arm 58 to which a link 59 is attached. The link 59 is reciprocated by means of a yoke co-operating with an eccentric on the main shaft 23 and in the manner fully set forth in the Muther et al patent, above referred to.

5 Mounted on the work support 1 is a strip deflector 60. The material, as shown in Fig. 4, is indicated at F and a trimmed off strip at f, and it is this trimmed off strip that engages the strip deflector and is diverted to one side.

10 When it is desired to shift the position of the line of stitching slightly from the edge which is being trimmed, the needle bar may be moved transversely through the arm 9 and the parts associated therewith and after the manner described in the Muther et al. patent. The amount of shift, however, given to the needle is limited. When it is 15 desired to increase to a considerable extent the distance between the line of stitching and the trimmed edge a new throat plate or ledger supporting bar is substituted, wherein in the ledger blade is made a different distance from the needle. The shiftable head is then moved transversely to bring the movable trimming blade into proper co-operation with the newly selected ledger blade. It will, therefore, be noted that I 20 have provided means for supporting the movable blade whereby it may be shifted transversely of the line of reciprocation of the needle to properly position the same for interchangeable throat plates having ledger 25 blades at different distances from the line of reciprocation of the needle. Furthermore, the movable blade is carried by a pivotal support and this pivotal support is spring 30 pressed so as to yieldingly force the movable blade laterally against the ledger blade. By varying the tension of the spring the pressure of the movable blade against the ledger blade may be increased or decreased as desired. By shifting the head carrying the 35 pivotal support and the limiting screw 51 the movable blade may be set at a slight angle to its path of reciprocation.

40 It has been found from practice that if the movable blade be set at a very slight angle, possibly half a degree or thereabouts, to the vertical better trimming results will be accomplished, and this setting of the trimming blade is permitted by the mechanism above described.

45 It is obvious that minor changes in the details of construction and the arrangement of the parts may be made without departing from the spirit of the invention as set forth in the appended claims.

50 Having thus described my invention, what I claim as new and desire to secure by Letters Patent of the United States is:—

55 1. The combination with stitch forming mechanism including a reciprocating needle, of a trimming mechanism comprising a stationary ledger blade, a movable blade co-operating therewith, a reciprocating support for said movable blade including devices whereby the blade is yieldingly forced laterally against the stationary ledger blade, and

means for bodily shifting said support for the movable blade on its reciprocating means in a direction at right angles to the line of reciprocation of said blade supporting means so that said blade may be positioned for co-operation with stationary trimming blades 70 of different widths.

2. The combination with stitch forming mechanism including a reciprocating needle, of a trimming mechanism comprising a stationary ledger blade, a movable blade co-operating therewith, a reciprocating support for said movable blade including devices whereby the blade is yieldingly forced laterally against the stationary ledger blade, and means for positively shifting said support for the movable blade on its reciprocating means so that said blade may be positioned for co-operation with stationary trimming blades 75 of different widths, and locking means 80 for locking the shiftable support in adjusted positions.

3. The combination with stitch forming mechanism including a reciprocating needle, of a trimming mechanism comprising a stationary ledger blade, a movable blade co-operating therewith, a pivotal support for said movable trimming blade, a shiftable head on which said pivotal support is 85 mounted, a spring for turning said pivotal support to press the movable blade against the ledger blade, and means for varying the tension of said spring. 90

4. The combination with stitch forming mechanism including a reciprocating needle, of a trimming mechanism comprising a stationary ledger blade, a movable blade co-operating therewith, a pivotal support for said movable trimming blade, a shiftable head on which said pivotal support is 95 mounted, a spring for turning said pivotal support to press the movable blade against the ledger blade, means for varying the tension of said spring, and a limiting screw for 100 limiting the movement of the pivotal support. 105

5. The combination with stitch forming mechanism including a reciprocating needle, of a trimming mechanism comprising a stationary ledger blade, a movable blade co-operating therewith, a pivotal support for said movable trimming blade, a shiftable head on which said pivotal support is mounted, a spring for turning said pivotal support to press the movable blade against the ledger blade, means for varying the tension of said spring, and means for positively 110 moving the shiftable head toward and from the line of reciprocation of the needle. 115

6. The combination with stitch forming mechanism including a reciprocating needle, of a trimming mechanism comprising a stationary ledger blade, a movable blade co-operating therewith, a pivotal support for 120 said movable trimming blade, a shiftable 125

head on which said pivotal support is mounted, a spring for turning said pivotal support to press the movable blade against the ledger blade, means for varying the tension of said spring, means for positively moving the shiftable head toward and from the line of reciprocation of the needle, and means for locking the shiftable head in adjusted positions.

7. The combination with stitch forming mechanism including a reciprocating needle, of a trimming mechanism comprising a stationary ledger blade, a movable blade co-operating therewith, a pivotal support on which said blade is mounted, a shiftable head carrying said pivotal support, a vertically reciprocating bracket carrying said shiftable head, said shiftable head having a ribbed connection with the bracket permitting the head to be moved horizontally toward and from the needle, an adjustable screw carried by the bracket and having connection with said shiftable head for positively moving the head toward and from the needle, a spring for turning said pivotal support on the shiftable head to yieldingly press the movable blade against the ledger blade, and means whereby the tension of said spring may be varied.

8. The combination with stitch forming mechanism including a reciprocating needle, of a trimming mechanism comprising a stationary ledger blade, a movable blade co-operating therewith, a pivotal support on which said movable blade is mounted, a shiftable head carrying said pivotal support, a vertically reciprocating bracket carrying said shiftable head, said shiftable head having a ribbed connection with the bracket permitting the head to be moved horizontally toward and from the needle, an adjustable screw carried by the bracket and having connection with said shiftable head for positively moving the head toward and from the needle, a spring for turning said pivotal support on the shiftable head to yieldingly press the movable blade against the ledger blade, means whereby the tension of said spring may be varied, and a limiting screw for limiting the movement of the movable blade in a direction toward the ledger blade.

9. The combination with stitch forming mechanism including a reciprocating needle, of a trimming mechanism comprising a stationary ledger blade, a movable blade co-operating therewith, a pivotal support, means for connecting said movable blade to

said pivotal support whereby said blade may be adjusted longitudinally on said pivotal support, a shiftable head on which said pivotal support is mounted, whereby said blade swings in a vertical plane toward and from the ledger blade, a spring engaging said pivotal support for yieldingly pressing the movable blade against the ledger blade, said shiftable head being capable of adjustment in a horizontal direction toward and from the line of reciprocation of the needle.

10. The combination with stitch forming mechanism including a reciprocating needle, of a trimming mechanism comprising a stationary ledger blade, a movable blade co-operating therewith, a pivotal support, means for connecting said movable blade to said pivotal support whereby said blade may be adjusted longitudinally on said pivotal support, a shiftable head on which said pivotal support is mounted, whereby said blade swings in a vertical plane toward and from the ledger blade, a spring engaging said pivotal support for yieldingly pressing the movable blade against the ledger blade, said shiftable head being capable of adjustment in a horizontal direction toward and from the line of reciprocation of the needle, a vertically reciprocating bracket on which said shiftable head is mounted, and a screw for positively moving said head on said bracket.

11. The combination with stitch forming mechanism including a reciprocating needle, of a trimming mechanism comprising a stationary ledger blade, a movable blade co-operating therewith, a pivotal support, means for connecting said movable blade to said pivotal support whereby said blade may be adjusted longitudinally on said pivotal support, a shiftable head on which said pivotal support is mounted, whereby said blade swings in a vertical plane toward and from the ledger blade, a spring engaging said pivotal support for yieldingly pressing the movable blade against the ledger blade, said shiftable head being capable of adjustment in a horizontal direction toward and from the line of reciprocation of the needle, a vertically reciprocating bracket on which said shiftable head is mounted, a screw for positively moving said head on said bracket, and clamping means for positively holding said shiftable head in adjusted positions.

In testimony whereof, I affix my signature.

JAMES R. MOFFATT.
